UNITED STATES PATENT OFFICE.

WILLIS L. FLEWELLIN AND ROBERT W. PITTS, OF BUFFALO GAP, SOUTH DAKOTA.

CATTLE-GUARD.

No. 895,548.

Specification of Letters Patent. Patented Aug. 11, 1908.

Application filed October 10, 1907. Serial No. 396,835.

To all whom it may concern:

Be it known that we, WILLIS L. FLEWELLIN and ROBERT W. PITTS, citizens of the United States, residing at Buffalo Gap, in the 5 county of Custer and State of South Dakota, have invented certain new and useful Improvements in Cattle-Guards, of which the following is a specification.

This invention relates to cattle guards, and 10 has for its object to provide an improved structure of such guard for railways, and to provide an exceedingly simple and inexpensive guard capable of effectively preventing cattle and other animals passing over it.

15 In the drawings forming a portion of this specification, and in which like numerals of reference indicate similar parts in the several views, Figure 1 is a top plan view of a railway track showing the arrangement of our 20 cattle guard at both sides of a crossing, Fig. 2 is a section on the line 2—2 of Fig. 1, Fig. 3 is a sectional view on the line 3—3 of Fig. 1, Fig. 4 is a perspective view of one of the rollers, Fig. 5 is a perspective view of one of the 25 bars composing the frame, Fig. 6 is a detail perspective view of one of the pins for the rollers.

Referring now to the drawings, there is 30 shown a cattle guard which consists of a frame 10 which is arranged between the tracks A, of a railway B, and this guard further consists of the frames 11 and 12 respectively, which are arranged at the outer sides of the tracks A. The frames 10 comprise a 35 plurality of vertically extending bars 13 and 14 which are arranged longitudinally of the tracks A. The bars 13 are arranged adjacent the inner sides of the tracks A and the bars 14 are arranged between the bars 13 and 40 at the center of the railway ties C, as shown, and at the outer ends of frames 11, and 12. Each of the bars 13 and 14 is provided with a vertically extending web portion 15, and at the lower ends, these bars are provided with 45 laterally extending flanges 16. Vertically extending passages 17 are formed in the flanges 16 for the reception of fastening devices 17', and by means of these fastening devices, it will be seen that the guard may be 50 securely held to the ties C.

In the web portions 15 of each of the bars 13 and 14, there are shown horizontally extending passages 18, and arranged between the bars 13 and 14, there are shown a series 55 of parallel spaced rollers 19 which extend

crosswise of the tracks A, and these rollers are provided with trunnions 20 which are arranged in horizontally extending passages 21 which are formed in the bars 13 and 14. It will thus be seen that the rollers are free to 60 revolve between the bars 13 and 14. Threaded passages 22 are formed in the rollers 19, and arranged in these passages there are shown the threaded ends 23 of pins 24, and these pins have their outer ends pointed as 65 shown at 25.

The longitudinally extending bars 13 and 14 have their upper edges serrated as shown at 26, and these serrated edges thus provide upwardly extending spurs 27 which are arranged adjacent the ends of the rollers 19 and in line therewith, and the spurs 28 which lie between the spaced rollers. The upper edges of the spurs are beveled as shown at 29 to form a knife edge 30. 75

The frames 11 and 12 are similar to the frame 10, but consist of but two longitudinally extending bars 13' and 14' respectively, and these bars are identical with the bars 13 and 14, and it is thought that a description 80 thereof is unnecessary. Rollers 19' are journaled between these bars in a manner similar to that shown in the frame 10.

From the construction described, it will be 85 seen that the rollers 19 and 19' are both of equal length, and the bars which are used in the construction of the frame 10 being identical with those shown in the frames 11 and 12, it will be seen that the frames 10, 11 and 12 may be formed of the same material. It 90 will further be seen, that the construction shown provides a strong and durable cattle guard which may be shipped with its parts in sections, and which may be easily and quickly set up at its place of use. 95

In use, it will be seen that if an attempt should be made by cattle or other animals to travel from the crossing to a point longitudinally of the tracks A, they would come 100 in contact with the guards at either side of the crossing, and in the movement of the cattle or animals it will be seen that the rollers will revolve, and the pins which are carried thereby will inflict sufficient pain and prevent further travel of the animals. 105

What is claimed is:

1. In a cattle guard the combination with longitudinally disposed parallel bars having base flanges and a plurality of vertically disposed spurs at their upper edges, said bars 110

having alining passages, of rollers disposed between said bars, trunnions carried by said rollers and disposed in said passages, and removable pins carried by said rollers.

- 5 2. The combination with revoluble spaced rollers having removable pins, and trunnions carried at the ends of said rollers, of a frame comprising longitudinally disposed parallel bars having base flanges, said bars having
10 alining passages in which said trunnions are disposed, sharpened spurs carried by said bars at their upper edges and located between the rollers at their ends.

In testimony whereof we affix our signatures, in presence of two witnesses.

WILLIS L. FLEWELLIN.
ROBERT W. PITTS.

Witnesses as to the signature of Willis L. Flewellin:
